SELECTIVE INFORMATION TAB DEVICE

Wesley W. Cline, Charleston, W. Va.

Application October 12, 1945, Serial No. 621,948

4 Claims. (Cl. 281—15)

1

This invention relates to a selective information device, and more particularly to a series of cards or tabs selectively interconnected in an interchangeable relationship.

An object of this invention is to provide a novel device having a series of superimposed cards pivotally connected together at one end and having means whereby the relative position of the cards may be changed without breaking the connection.

Another object of this invention is to provide a novel information card device having a series of superimposed cards permanently connected together at one end in such manner that any card may be moved to the top position without breaking the connection.

It is a further object of this invention to provide a novel selective information tab device in which the tabs are pivotally connected together and in which means are provided to permit any tab to be pivoted about its connection to a position over all the other tabs.

Other objects of this invention will appear from the following specification and claims and from the accompanying drawing illustrating the invention wherein:

Figure 1 is a bottom view of the selective information device of this invention with part of the device cut away to show the interior construction;

Figure 2 is a sectional view of part of the device taken on line 2—2 of Figure 1 and showing the cam finger for camming the cards to the topmost position;

Figure 3 is a bottom view of the device with part of the device cut away and with the cards in a pivotally offset position;

Figure 4 is an elevational view of the device looking in the direction of the arrows 4—4 in Figure 3; and

Figure 5 is an enlarged elevational view looking at the pivotal end of the device showing one of the cards being moved to its new position at the top.

Referring to the drawing, the device has a series of cards or tabs 1 to 8, inclusive, in superimposed relationship and pivotally connected together at one end by the bolt 9. The device illustrated in Figure 5 shows the use of eight information tabs but any number, more or less, may be used. At the top and bottom of the cards or tabs are positioned protective cover sheets, 10 at the top and 11 at the bottom. These cover sheets are made of any suitable transparent material so that the cards beneath will be visible therethrough. Thus the information on the top

2

card 1, Figure 5, will be visible through the transparent cover sheet 10. The cover sheets have openings at the pivoted end of the device to receive the bolt 9. Over cover sheet 10 is a washer disc 12 and under cover sheet 11 is a washer disc 13, the washer discs being held in position by the bolt 9 passing through openings therein.

The bottom washer 13 has a prong or cam finger 14 welded or otherwise fixed to the inner face of the washer. As seen in Figures 3 and 5, the prong 14 extends up from the washer 13 through a slit 11' in the cover sheet 11 and into a space 15 which is formed by cutting out portions slightly greater than a quadrant from each of the tabs 1 to 8, inclusive. The cut-out portions are superimposed to form the chamber or space 15. As seen in Figure 3, the line of cut passes through the pivotal axis of the cards. In order to prevent the cards from being disconnected from each other in the pivotal region, each of the cards 1 to 8, inclusive, each cover sheet 10 and 11, and each washer 12 and 13 is provided with a circumferential hollow rib, designated by the numeral 16 in the cards, the numeral 17 in the cover sheets, and the numeral 18 in the washers. These ribs are superimposed and fit into each other to prevent separation of the cards in the plane of the cards. When all or one of the cards is pivoted to an offset position its pivotal axis is fixed by the coaction of its hollow circumferential rib 16 with adjacent ribs 16 or 17, the circumferential ribs coacting with each other in all positions of the tabs 1 to 8, inclusive. Each of the cards 1 to 8, inclusive, has its edges at the cut-out portion beveled as shown at 18' in Figure 5 so that as a card is pivoted, for example, card 2 as shown in Figure 5, its forward edge 19 is cammed upwardly by the cam finger 14 to a position over the card 1. The cover sheet 10 and washer 12 are formed with bulges 20 and 21, respectively, adjacent the tip of the cam finger 14 to assist in guiding the forward edge 19 of card 2 above card 1.

The right end of the device, as seen in Figures 1 to 4, is provided with a pair of bolts 22 passing through the cover sheets 10 and 11 and through a filler member 23 placed between the cover sheets. The filler member may consist of a number of superimposed strips of any suitable material providing a total depth equal to the depth presented by the tabs 1 to 8. The inner side of the filler member 23 is provided with a stop 24 which coacts with a stop 25 formed on each of the cards 1 to 8. Each of the cover members 10 and 11 have cutouts 26 to enable pushing the cards or any one

of them to a position offset from the cover sheets to facilitate pivotal movement.

Each of the tabs or cards 1 to 8 have data and information of some sort imprinted or marked thereon. When the cards are in superimposed position as shown in Figure 1, only the data on the top card 1 is visible through the transparent cover sheet 10. If an operator desires to obtain data from one of the other cards, for example, card 2, he pivots all the cards to an offset position as shown in Figure 3, pulls card 2 ahead of the other cards, and returns the other cards to their original position. He then continues to rotate the card 2 clockwise about the bolt 9 as a pivot until the card 2 has been rotated to an extent of about 180°, the position shown in Figure 5. When the forward edge 19 of the card 2, as shown in Figure 5, reaches the cam finger 14, said forward edge is cammed upwardly to a position immediately under the cover sheet 10 and over the top card 1. Continued movement of the card 2 results in the whole card 2 being cammed up into the top superimposed position over card 1. Thus the data on card 2 will be directly visible through the transparent cover sheet 10. Likewise any other card can be similarly pivoted to the topmost position. During the pivotal action, the cards are held against separation at the pivot by the circumferential hollow ribs held in engagement with each other by the washers 12 and 13 and bolt 9. The stops 24 and 25 permit pivotal movement in only one direction.

While a certain specific embodiment of this invention has been shown it will be understood that various modifications may be made within the spirit of the invention. Therefore no limitations on the invention are intended other than are imposed by the scope of the appended claims.

I claim:

1. A selective information tab device comprising a series of tabs arranged in superimposed relation, each of said tabs having a circumferential hollow rib, the respective ribs coacting with each other to hold said tabs together in a permanent manner, an end of each of said tabs being provided with a cut-out portion, a connection pivotally securing said tabs together, the cut-out portions of the respective tabs enclosing said connection and forming a hollow space, and a cam finger carried by said connection and extending upwardly through said space for camming any one of the tabs to a position over all of the other tabs upon pivotal movement of said one tab.

2. A selective information tab device comprising a pair of disk washers arranged in superimposed relation and spaced from each other, an upstanding pin passing through said washers and secured thereto, a series of tabs arranged in superimposed relation interposed between said wash-

ers, an end of each of said tabs being mounted for pivotal movement about said pin, the end of each of said tabs being provided with a cut-out portion, the cut-out portions of the respective tabs enclosing the pivotal mounting and forming a hollow space, and a cam finger carried by one of said washers and extending upwardly through said space for camming any one of the tabs to a position over all the other tabs upon pivotal movement of said one tab.

3. A selective information tab device comprising a pair of disk washers arranged in superimposed relation and spaced from each other, an upstanding pin passing through said washers and secured thereto, a series of tabs arranged in superimposed relation interposed between said washers, an end of each of said tabs being mounted for pivotal movement about said pin, the end of each of said tabs being provided with a cut-out portion having its bounding edges beveled, the cut-out portions of the respective tabs enclosing the pivotal mounting and forming a hollow space, and a cam finger carried by one of said washers, there being an outward bulge on the other of said washers, said cam finger extending into said space to a position adjacent said bulge whereby when one of said tabs is pivoted about said pin, its beveled edge is cammed upwardly by said finger to a position above the topmost tab between the tip of said finger and said bulge.

4. A selective information tab device comprising a pair of disk washers arranged in superimposed relation and spaced from each other, an upstanding pin passing through said washers and secured thereto, a series of tabs arranged in superimposed relation interposed between said washers, each of said tabs having a circumferential hollow rib, the respective ribs coacting with each other to hold said tabs together in a permanent manner, an end of each of said tabs being mounted for pivotal movement about said pin, the end of each of said tabs being provided with a quadrant-shaped cut-out portion, the cut-out portions of the respective tabs enclosing the pivotal mounting and forming a hollow space, and a cam finger carried by one of said washers and extending upwardly through said space for camming any one of the tabs to a position over all of the tabs upon pivotal movement of said one tab.
